(57) **CLAIM**

The ornamental design for a combination vacuum packaging machine, as shown and described.

DESCRIPTION

FIG. 1 is a front perspective of a combination vacuum packaging machine embodying our design;

FIG. 2 is a front elevation of the combination vacuum packaging machine shown in FIG. 1;

FIG. 3 is a right side elevation of the combination vacuum packaging machine shown in FIGS. 1 and 2, with the opposite side elevational view being a mirror image thereof;

FIG. 4 is a rear elevation of the combination vacuum packaging machine shown in FIGS. 1-3; and,

FIG. 5 is a top view of the combination vacuum packaging machine shown in FIGS. 1-4.

The dashed broken lines are directed to environment. The dot-dash broken lines are directed to boundaries that form no part of the claimed design. None of the broken lines form part of the claimed design.
